US00D871685S

(12) **United States Design Patent** (10) **Patent No.:** **US D871,685 S**
(45) **Date of Patent:** **** Dec. 31, 2019**

(54) **TRAINING TOOL**

(71) Applicant: **ANIMAL EXPERT, LLC**, Agoura Hills, CA (US)

(72) Inventors: **Brandon Parrish McMillan**, Los Angeles, CA (US); **Jack Renforth**, Azle, TX (US); **Nicholas Baker**, Fort Worth, TX (US)

(73) Assignee: **ANIMAL EXPERT, LLC**, Agoura Hills, CA (US)

(**) Term: **15 Years**

(21) Appl. No.: **29/597,753**

(22) Filed: **Mar. 20, 2017**

(51) LOC (12) Cl. **30-99**

(52) U.S. Cl.

USPC **D30/160**
